(57) **CLAIM**

The ornamental design for a portable chip reader, as shown and described.

DESCRIPTION

FIG. 1 is a top perspective view of a portable chip reader showing our new ornamental design;

FIG. 2 is a bottom perspective view of the portable chip reader shown in FIG. 1;

FIG. 3 is a top perspective view of the portable chip reader shown in FIG. 1;

FIG. 4 is a top view of the portable chip reader shown in FIG. 1;

FIG. 5 is bottom view of the portable chip reader shown in FIG. 1;

FIG. 6 is a front view of the portable chip reader shown in FIG. 1;

FIG. 7 is a rear view of the portable chip reader shown in FIG. 1;

FIG. 8 is a right side view of the portable chip reader shown in FIG. 1; and,

FIG. 9 is a left side view of the portable chip reader shown in FIG. 1.

Broken lines and portions contained within broken lines are not claimed.
